CLAIM

The ornamental design for a POS optical scanning station, as shown and described.

DESCRIPTION

FIG. 1 is a perspective view of a POS optical scanning station showing our new design;

FIG. 2 is a perspective view of a modified form thereof;

FIG. 3 is a cross-sectional view taken along line 3—3 of

FIG. 1; and

FIG. 4 is a cross-sectional view taken along line 4—4 of

FIG. 2.

FIG. 1

FIG. 3

FIG. 2

FIG. 4
